UNITED STATES PATENT OFFICE

2,506,631

WINDOW

John K. Daniels, Minneapolis, Minn.

Application September 4, 1945, Serial No. 614,182

2 Claims. (Cl. 20—48)

1

My present invention relates to improvements in windows and, more particularly, to a double hung window.

The objects of this invention are: first, to provide a window having all of the advantages of a double hung window combined with those of a casement window; second, to provide a sash of a double hung window with duplex casement windows spaced apart to leave a relatively deep air insulating space therebetween; third, to provide novel means for mounting the glass pane of a casement window; and fourth, to provide novel means for hinging a casement window.

These and other objects of the invention will be apparent from the following description, reference being had to the drawings.

To the above end, generally stated, the invention consists of the novel construction and arrangement, hereinafter described and defined in the claims.

In the accompanying drawings, which illustrate the invention, like characters indicate like parts throughout the several views.

Referring to the drawings:

Fig. 1 is an elevation of a double hung window having the invention embodied therein;

Fig. 2 is an elevation of one of the casement windows before the same is mounted in one of the sash and having its binding partly applied thereto;

Fig. 3 is a fragmentary view in section taken on the line 3—3 of Fig. 1, on an enlarged scale;

Fig. 4 is a fragmentary view partly in plan and partly in section taken on the line 4—4 of Fig. 1, on the same scale as Fig. 3 and showing the windows open instead of closed as shown in Fig. 1;

Fig. 5 is a fragmentary detail view in elevation showing the hinge connection between the inner casement window and the sash;

Fig. 6 is a fragmentary detail view in section taken on the line 6—6 of Fig. 5;

Fig. 7 is a plan view of the upper hinged stud and a portion of the connected binding;

Fig. 8 is a fragmentary side elevation of one of the casement windows with certain parts thereof segregated, and on an enlarged scale;

Fig. 9 is a plan view of the parts shown in Fig. 8; and

Fig. 10 is a view similar to Fig. 4, but on a reduced scale and showing a slight modification.

The upper and lower sash 12 of the double hung window, shown in Fig. 1, are mounted in a frame 13. The sash 12 are somewhat different from the standard sash in that the bead 14 is on the outside thereof instead of on the inside and

2

takes the place of the customary putty joint. Formed in the inner face of the sash 12 is a rectangular rabbet 15. A second rabbet 16, similar to the rabbet 15, is formed in the sash 12 back of the bead 14.

Inner and outer casement windows 17 are mounted in the rabbets 15 and 16, respectively, of each sash 12. The casement windows 17 are identical in the one with the other with the exception that the outer window 17 is necessarily slightly smaller than the inner window 17 to permit the formation of the rabbet 16 therefor.

Each casement window 17 includes a rectangular glass pane 18 and a binding 19 therefor. This binding 19 is a metal channel, the longitudinal edge portions of which are folded inwardly upon the sides of said channel to trim and reinforce the binding 19 and also afford fillets 20.

Three sections of the binding 19, indicated by the numeral 21, are rigidly connected at right angles to each other. The other or fourth section of the binding 19 is indicated by the numeral 22. End portions of the sections 21 are turned outwardly and rolled to form axially aligned cores 23 for hinge studs, as will presently appear. The sides of the sections 21 at their ends are beveled at 24.

The sides of the section 22 at the end portions thereof, are beveled and notched at 25. The end portions 26 of the section 22 outwardly of the notches and bevels 25 are of the same length as the cores 23.

To mount one of the glass panes 18 in its binding 19, said pane is first slid edgewise into the sections 21. Then section 22 is placed over the other or exposed edge portion of the glass pane 18. The end portions 26 of the section 22 are rolled around the cores 23 to rigidly connect the sections 21 and 22 and also form hinge studs 27. The attachment of the section 22 to the section 21 brings their beveled edges 24 and 25 into abutting relation and form miter joints between said sections.

Upper and lower double hinge plates 28, for the hinge studs 27, are secured to each sash 12 by screws 29. These hinge plates 28 are bent to fit in the rabbets 15 and 16 and have holes 30 through which the hinge studs 27 extend. Obviously, the hinge plates 28 mount the duplex casement windows 17 in the sash 12 for inward swinging movement where they may be easily cleaned. Either the sash 12 or the casement windows 17 may be opened for the purpose of ventilation.

Secured in the rabbet 15 is a weatherstrip 31 on which the respective casement window 17 seats.

The rabbets 15 and 16 are located to position the casement windows 17 a considerable distance apart in order to leave an efficient air insulating space between said windows. The duplex casement windows 17 eliminate the necessity of the customary storm window.

It is intended that the casement windows 17 for double hung sash be carried in stock. In case one of the windows in a double hung sash is broken, it would only be necessary to remove the same, by detaching the hinge plates 28, and substituting a new one therefor. The use of my casement window eliminates all glazing operations.

At the time the glass pane 18 is mounted in its binding 19, cement 32 may be placed in said binding to firmly connect the glass pane 18 and the binding 19. The fillets 20 prevent the cement 32 from squeezing between the glass pane 18 and its binding 19. The sides of the binding 19, before a glass pane 18 is mounted therein, are in slightly converging relation so that they are sprung apart by the placing of the glass pane 18 therein. This causes the binding 19 to pinch the glass pane 18 and prevent rattle and reduce air leakage.

Referring now to the modification shown in Fig. 10, parts that correspond to like parts in the other views have been given the same reference numerals followed by a prime. The only difference in the structure shown in Fig. 10 is that the casement windows are hinged on opposite sides of the sash.

From what has been said, it will be understood that the invention described is capable of modifications as to details of construction and arrangement within the scope of the invention herein disclosed and claimed.

It will, of course, be understood that the double hung window and the casement windows will be provided with suitable fastening devices for hold-

ing the same closed. Likewise, the casement windows may be provided with suitable devices for holding the same open.

What I claim is:

5 1. In a casement window, a glass pane, and a binding in which said pane is mounted, said binding comprising a main section and an auxiliary section, the end portions of the main section being turned outwardly into axial alignment, said auxiliary section having end extensions that are interlocked with the outturned end portions of the main section to rigidly connect the two sections and form hinge studs.

10 2. In a casement window, a glass pane, and a channel binding in which said pane is mounted, said binding comprising a main section and an auxiliary section, the end portions of the main section being turned outwardly into axial alignment and folded to form cores, said auxiliary section having end extensions that are folded around said cores to rigidly connect the two sections and form hinge studs.

JOHN K. DANIELS.
